UNITED STATES PATENT OFFICE.

WILLIAM REID, OF GENEVA, NEW YORK.

COOKING STOVE OR RANGE.

SPECIFICATION forming part of Letters Patent No. 773,081, dated October 25, 1904.

Application filed March 9, 1903. Serial No. 146,994. (No model.)

To all whom it may concern:

Be it known that I, WILLIAM REID, a citizen of the United States, residing at Geneva, county of Ontario, and State of New York, have invented certain new and useful Improvements in Cooking Stoves or Ranges, of which the following is a specification.

The invention relates to such improvements; and it consists of the novel construction and combination of parts hereinafter described and subsequently claimed.

Reference may be had to the accompanying drawings and the reference characters marked thereon, which form a part of this specification.

Similar characters refer to similar parts in the several figures.

Figure 1 of the drawings is a top plan view, partly in horizontal section, of a cooking stove or range embodying this invention.

Fig. 2 is a vertical longitudinal section of the same, taken on the broken line 2 2 in Fig. 1 transversely of the fire-box. Fig. 3 is a vertical cross-section of the same, taken on the broken line 3 3 in Fig. 1. Fig. 4 is a view in front elevation of a broken-way portion of the front end of the range, showing one of the depending hangers provided with an open bearing for the outer journal of the grate-bar.

The invention relates more particularly to the permanent grate construction of a stove or range having a plurality of kettle-holes above and open to the fire-box.

The principal object of my invention is to provide a cooking-stove which is adapted without change of structure and by simple operation of its grate-bars to produce either a uniform degree of heat throughout the fire-box and beneath both kettle-holes or any desired relative degrees of heat beneath the respective kettle-holes or any desired degree of heat beneath one kettle-hole without the presence of fire beneath another kettle-hole.

The nature of the invention and other objects thereof will appear in connection with the following description.

In the drawings the invention is shown in its preferred application to a range having the fire-box 1 extending transversely of the

range at its front end 2 and lined with fire-brick 3, mounted in the usual manner upon the bed-plate 4. The fire-box is inclosed at its upper end by the stove-top 5, provided with kettle-holes 6, two of which are open to the fire-box and arranged longitudinally thereof. The kettle-holes may be provided with removable covers 7 in the usual manner. Extending longitudinally of the fire-box, near its lower end and just beneath the bed-plate 4, is a pair of slideways, one of which, 8, is formed on the inner side of the front end 2 of the stove and the other, 9, formed on the outer side of the front oven-plate 10. These slideways guide the grate-frame 11 as the same is being inserted or removed and support the same beneath the fire-box.

The range is provided with an opening 12 in its front side at one end of said slideways, adapted to permit the passage therethrough of the grate-frame in inserting and removing the same. This opening may be closed by a removable door or cover 13, which may be constructed in any known manner.

The grate-frame is provided along its rear side with bearings 14 for the inner journals 15 of the grate-bars 16, the outer journals 17 of which are mounted in bearings in the hangers 18, depending from the front end of the stove. The bearings for the outer journals of the grate-bars are thus arranged along the front side of the fire-box and, with the bearings 14 on the rear side of the grate-frame, are adapted to support the grate-bars transversely of the fire-box. The bearings in the hangers 18 are preferably made to open laterally to facilitate the insertion and removal of the grate-bar journals, which are held in the bearings by means of a retaining-plate 19, apertured to receive and inclose the outer ends of the grate-bar journals and adapted to be connected with an ear 20 on the front end of the stove by means of a pin 21 inserted through an aperture in said ear and engageable with the outside of said retaining-plate, which is apertured to receive said ear.

The grate-bars may be operated in any known manner.

It will thus be seen that by extending the grate-bars transversely—that is, the short

way—across the fire-box certain of the grate-bars will be located beneath one of the kettle-holes and certain others beneath the other kettle-hole, and by operating the grate-bars 5 beneath a selected kettle-hole independently of the other grate-bars combustion can be localized beneath said kettle-hole while the fire may be retained in a banked condition or permitted to wholly die out beneath the other 10 kettle-hole. It is thus possible to quickly adapt the range to varying demands upon its resources, and yet at all times to secure rapid combustion and a high degree of heat throughout or in any part of the fire-box and, if desired, 15 different degrees of heat beneath the respective kettle-holes, permitting great economy in the use of fuel and in warm weather permitting the use of the range for cooking purposes for limited culinary requirements 20 without unnecessarily increasing the temperature of the surrounding atmosphere. By proper manipulation of the respective sets of grate-bars the heat beneath the respective kettle-holes can be accurately regulated to 25 adapt it for cooking different articles requiring different degrees of heat for their proper preparation. As shown, two of the bars are located beneath one kettle-hole and are connected together to rotate in unison by intermeshing gears 22, the outer journals of one 30 of said bars being extended and provided with an angular end 23 to adapt it to receive a shaker. Two other grate-bars are arranged beneath the other kettle-hole and in like manner connected together by intermeshing gears 35 24, the outer journal of one of said bars being extended and provided with an angular end 25, adapted to receive a shaker.

The outer ends of the grate-bar journals, 40 their connecting-gears, and supporting mechanism are inclosed by the front draft-door 26, which is provided with apertures 27, adapted to permit the insertion therethrough of the end of the shaker when applying the same to 45 the angular ends of the respective grate-bars. These apertures 27 may be closed by a movable cap or cover 28.

It will be seen that the slideway 9 is open and unobstructed at the right-hand end of 50 Fig. 3 adjacent to the door 13. The other slideway 8 is open at the same end in the same manner. These slideways do not appear in the sectional part of Fig. 1, because the plane of the section extends through the upper portion of the fire-box where the same is lined 55 with fire-brick. Both said slideways being open at the end adjacent to the door, it will be seen that if the door be opened and the grate-bars detached there is nothing to prevent the 60 grate-frame 11 from being slid endwise out through the open ends of the slideways 8 and 9 and the adjacent door-opening. When, however, the grate-bars are seated at one end in the grate-frame and at the other end in the 65 hangers 18, fixed to the stove-body, said

bars extend transversely of the line of movement of the grate-frame to withdraw the same as above explained, thus serving to lock the grate-frame in position so long as the bars remain in position; but when the grate-bars 70 are removed the grate-frame can be slid endwise out through the opening 12 in the front side of the stove.

This invention permits the use of comparatively short grate-bars which extend across 75 the oblong fire-box in the direction of its shorter dimension, said bars being more rigid and less likely to sag or to become cracked or warped by heat than comparatively long bars 80 extended longitudinally of the fire-box.

By extending the grate-bars transversely of the fire-box their outer ends are caused to project at the front end of the range and within the limits of the hearth-plate 29, so that the outside dimensions of the range are 85 not increased by the projecting grate-bar journals or their connecting and supporting mechanisms, as is the case where grate-bars are arranged longitudinally of the fire-box with their outer journals projecting through 90 the front side of the range.

What I claim as new, and desire to secure by Letters Patent, is—

1. In a cooking stove or range, the combination with the fire-box; of a stove-top provided with a plurality of kettle-holes arranged longitudinally of, and open to, the fire-box; a removable grate-frame in the fire-box; separate movable grate-bars extending transversely of the fire-box beneath the respective 95 kettle-holes and having bearings in said grate-frame, said grate-bars together forming the whole permanent bottom of the fire-box, and means for operating certain of the grate-bars 100 independently of each other. 105

2. In a cooking stove or range, the combination with the fire-box; of a stove-top provided with a pair of kettle-holes arranged above and open to the fire-box; two pairs of 110 rotatory grate-bars arranged transversely of the fire-box, one pair beneath one, and the other pair beneath the other, of said kettle-holes; and means for operating the grate-bars, one pair independently of the other. 115

3. In a cooking stove or range, the combination with the stove-body having a fire-box in its front end and provided with a side opening at one end of the fire-box; slideways extending longitudinally of the fire-box near its lower end opening at their ends adjacent to said side opening; and grate-bar bearings located along the front side of the fire-box; of a bearing-frame insertible and removable along said slideways through the open ends thereof and said side opening; and grate-bars 125 extending transversely of the fire-box and bearing-frame mounted at their inner ends in bearings on said frame, and at their outer ends in said grate-bar bearings located along the front side of the fire-box, whereby the bear- 130

ing-frame is locked in position by the grate-bars.

4. In a stove or range, the combination with a fire-box; of a stove-top provided with 5 a plurality of kettle-holes arranged above and open to the fire-box; a separate permanent grate structure located beneath each of said kettle-holes and extending substantially across the fire-box, each of said grate 10 structures being adapted to be operated independently of the other; and means projecting exteriorly of the fire-box for operating each of said grate structures independently of the other whereby, by mere operation of the 15 grate structures, a uniform degree of heat can be maintained throughout the fire-box beneath both kettle-holes, or different relative degrees of heat can be maintained beneath the respective kettle-holes, or the desired degree of heat can be maintained beneath one 20

kettle-hole without the presence of fire beneath the other kettle-hole.

5. In a cooking stove or range, the combination with a stove-body having a fire-box extending across its front end, and a hearth extending forwardly from the front side of the fire-box in a plane below the fire-box; of grate-bars extending longitudinally of the stove and transversely of its fire-box, said grate-bars having their outer ends projecting 25 at the front end of the stove within the limits of the hearth, said projecting ends being adapted to receive operating mechanism.

In testimony whereof I have hereunto set my hand this 6th day of March, 1903.

WM. REID.
